Primary Examiner — Ian Simmons*Assistant Examiner* — Shannon Morgan(74) *Attorney, Agent, or Firm* — Mahamedи Paradice LLP(57) **CLAIM**

The ornamental design for a computing device display screen with graphical user interface, as shown and described.

DESCRIPTION

The FIGURE is a front view of a computing device display screen with graphical user interface showing the new design. The broken lines shown in the FIGURE represent portions of the computing device display screen and graphical user interface that form no part of the claimed design.

1 Claim, 1 Drawing Sheet(56)
